CLASP

Charles A. Domler, Providence, R. I., assignor to
The Hadley Company, Inc., Providence, R. I.,
a corporation of Rhode Island

Application January 1, 1943, Serial No. 471,031

3 Claims. (Cl. 24—241)

This invention relates to clasps such, for example, as are used in wrist watch bracelets, necklaces, etc.

The principal objects of the invention are to provide a clasp having safety catches which are so designed that both must be separately released, but upon the closing or fastening of one catch the other is automatically closed or moved to locking position; and to provide a clasp of the aforesaid type which is of simple design and of pleasing appearance, which is of strong and durable construction, and which is reliable and efficient in operation.

Further objects will be apparent from a consideration of the following description and accompanying drawing, wherein:

Fig. 1 is a top plan view of a clasp constructed in accordance with the present invention;

Fig. 2 is a side elevation of the clasp shown in Fig. 1;

Fig. 3 is an enlarged central longitudinal section of the clasp showing the slidable catch in locking position;

Fig. 4 is a view similar to Fig. 3 but showing both catches in released position;

Fig. 5 is a section on line 5—5 of Fig. 3;

Fig. 6 is a section on the line 6—6 of Fig. 4; and

Fig. 7 is a perspective view of the slidable catch.

The embodiment herein shown comprises a clasp 1 integral with a coupling member 2 adapted to hold one end of a bracelet B and which may be of any conventional design and construction, and a coupling member 3 adapted to hold the other end of the bracelet, the coupling 3 having a loop 4 by means of which it is detachably secured to the clasp 1.

The clasp 1 comprises a substantially hollow body member having a top wall 5 provided with a longitudinally extending slot 6 (Figs. 3 and 6), and side walls 8 and 9 which diverge beyond the body of the clasp and merge with the coupling member 2. The side walls 8 and 9 are integral with a bottom wall 10 which is slotted to provide flanges 11, as shown in Figs. 3 to 5. The outer end of the top wall is cut to provide a pair of spaced ears 12 (Figs. 4 to 6) which are bent downwardly a slight amount to provide abutments, the utility of which is hereinafter pointed out. The side walls are formed with aligned notches which define a transversely extending recess 15 adjacent to one end of the body member, the recess 15 being adapted to receive the loop 4 of coupling 3, as shown in Figs. 1 and 2. The bottom wall 10 is provided with an inwardly projecting finger 18 (Figs. 3 and 4) which is in-

clined relative to the bottom wall toward the recess 15.

The top, side and bottom walls define a slide-way which receives a movable catch 20 having a body portion shaped loosely to fit within the slide-way, and having sufficient clearance between its upper and lower faces on the one hand with the top and bottom walls of the clasp, on the other hand, to permit a slight rocking or tilting movement. The catch 20 is formed with an upwardly projecting head 21 which extends through the slot 6 and this head is shaped to provide a nose 22 which overhangs the outer end of the catch sufficiently to form a recess cooperating with the recess 15 to accommodate the loop 4 when the catch is in locking position, as shown in Figs. 1 to 3. The bottom of the catch is provided with a longitudinally extending slot 25 (Fig. 4) shaped to accommodate the upper end of a coil compression spring 26, the lower end of which is seated on or carried by the finger 18.

The construction and arrangement of parts are such that when catch 20 is manually moved against the action of spring 26 from locking position (Fig. 3) inwardly to released position (Fig. 4), in which the nose 22 is substantially clear of the recess 15 and the front lateral edges 28 of the catch are disposed inwardly of the abutments 12, the spring 26, acting upwardly at an angle, is effective to tilt or rock the catch so that the edges 28 of its body portion are brought into and held in engagement with the abutments 12, as shown in Figs. 4 and 6; and when the catch 20 has thus been "cocked," its head 21 may be depressed so as to disengage the edges 28 from abutments 12, whereupon the spring becomes effective to slide the catch outwardly to and hold it in locking position, as shown in Fig. 3. The abutments 12 not only cooperate with the side and bottom walls to guide the catch to and from locking position, but also cooperate with the spring 26 to provide a releasable lock for holding the catch in released position; and it will be further observed that when in the latter position 45 the head 21 extends upwardly from the top wall 5 a distance slightly greater than it does when in locking position.

The end of the body member adjacent to the recess 15 is provided with a transversely extending pintle 39 which supports a second catch or locking lever 31 for pivotal movement toward and away from the top wall 5. The design of the catch 31 is such that when swung to locking position (Fig. 2) it engages the head 21 of the catch 55 20 when the latter is in released position, and

depresses it sufficiently to effect disengagement of the edges 28 from abutments 12, thereby permitting the spring 26 to slide the catch 20 to locking position.

The free end of the catch 31 is provided with a depending resilient finger 34 adapted to snap about depending lugs 35 formed integral with the top wall 5, as shown in Fig. 3. The free end of the catch 31 is also formed with an upstanding nib 36 which provides a finger piece by means of which the catch may be pried outwardly from closed position, thus permitting the catch to be swung to open position, as shown by the full lines of Fig. 4.

When both catches are in open position (Fig. 4) the loop 4 may be dropped over the pivotal catch 31 directly into the recess 15, and then the catch 31 may be swung to closed position, whereupon the slideway catch 20 is automatically moved to locking position as shown in Fig. 3. When the parts are in closed position the finger 34 is effective to hold the pivotal catch closed and the spring 26 is likewise effective to hold the slideway catch in closed position. In order to release the catches, it is merely necessary to swing the pivotal catch 31 to upright position and then slide the catch 20 inwardly to released position, whereupon the spring 26 becomes effective to tilt it upwardly into engagement with the abutments 12, as above explained.

While I have shown and described one desirable embodiment of the invention, it is to be understood that this disclosure is for the purpose of illustration, and that various changes in shape, proportion and arrangement of parts, as well as the substitution of equivalent elements for those herein shown and described, may be made without departing from the spirit and scope of the invention as set forth in the appended claims.

I claim:

1. A safety clasp comprising a body member having side and bottom walls defining a slideway and an inwardly projecting part forming a fixed abutment, the side walls having aligned recessed portions adjacent to one end to provide an opening for removably receiving a loop-like coupling member, a catch loosely mounted in said slideway and movable therein from a locking position, wherein the coupling member is held within said recess, to a released position, wherein the coupling member may be removed from said recess, said catch being formed with a shoulder engageable with said abutment so that when the catch is moved to released position it may be tipped so as to bring said shoulder into engagement with said abutment, and resilient means acting on said catch at such an angle that when said catch is in released position, said resilient means operates to tip it to a position wherein said shoulder is brought into and held in engagement with said abutment, said resilient means being operative when said shoulder is disengaged from said

abutment to move said catch to and hold it in locking position.

2. A safety clasp comprising a body member having side and bottom walls defining a slideway and an inwardly projecting part forming a fixed abutment, the side walls having aligned recessed portions adjacent to one end to provide an opening for removably receiving a looplike coupling member, a catch loosely mounted in said slideway and movable therein from a locking position, wherein the coupling member is held within said recess, to a released position, wherein the coupling member may be removed from said recess, said catch being formed with a shoulder engageable with said abutment so that when the catch is moved to released position it may be tipped so as to bring said shoulder into engagement with said abutment, resilient means acting on said catch at such an angle that when said catch is in released position, said resilient means operates to tip it to a position wherein said shoulder is brought into and held in engagement with said abutment, said resilient means being operative when said shoulder is disengaged from said abutment to move said catch to and hold it in locking position, and a second catch mounted on said body member to move toward and away from said recessed portion, said second catch being engageable with the first catch when the latter is in released position to effect disengagement of said shoulder with said abutment and thereby permit said resilient means to move the first catch to locking position.

3. A clasp comprising a body member having side and bottom walls defining a slideway and an inwardly extending ear forming a fixed abutment between the ends of said body member, the side walls having recess portions adjacent to one end for removably receiving a coupling member and the bottom wall having an upwardly extending finger spaced inwardly from and inclined toward said recess, a catch loosely mounted in said slideway and formed with a shoulder engageable with said abutment, said catch being movable from locking position, wherein the catch is held within said recess, to a released position, wherein the catch may be tipped to a position wherein said shoulder is held in engagement with said abutment, a coil spring carried by said finger and acting on said catch when in released position to tip it to a position wherein said shoulder is held in engagement with said abutment, said spring being operative when said shoulder is disengaged from said abutment to move said catch to and hold it in locking position, and a second catch pivotally mounted on said body member to swing toward and away from said recess so as to engage and depress the first catch when in released position, thereby to effect disengagement of said shoulder with said abutment and permit said spring to move said first catch to locking position.

CHARLES A. DOMLER.
